UNITED STATES PATENT OFFICE.

GABRIEL H. W. DOOSE, OF SAN FRANCISCO, CALIFORNIA.

GARMENT HANGER AND STRETCHER.

1,070,236.

Specification of Letters Patent. Patented Aug. 12, 1913.

Application filed August 21, 1912. Serial No. 716,247.

To all whom it may concern:

Be it known that I, GABRIEL H. W. DOOSE, a citizen of the United States, residing at San Francisco, in the county of San Francisco and State of California, have invented new and useful Improvements in Garment Hangers and Stretchers, of which the following is a specification.

This invention relates to garment hangers and crease formers, and has for an object to provide means designed particularly for the purpose of stretching trousers and for maintaining the desired crease in the leg of the trousers.

Another object of the invention is to provide a combined hanger and crease former that will include an extensible structure which can be readily adjusted to fit trousers of different sizes.

A still further object of the invention is to provide means whereby the combined hanger and crease former can be folded into a very compact package for storage or for shipment.

In the drawing, forming a portion of this specification and in which like numerals of reference indicate similar parts in the several views: Figure 1 is a side view showing my improved hanger and crease former operatively arranged in a trousers leg. Fig. 2 is a perspective view of the hanger. Fig. 3 is a section on line 3—3 of Fig. 1.

The hanger comprises tubular members 1 and 2 which are identically constructed, one of the members being designed for the purpose of forming the front crease in the trousers leg and the other being adapted to form the back crease in the leg. Each member is substantially of elliptical configuration in cross section so that each presents a relatively narrow crease-forming surface 3. The members are connected with each other by the laterally adjustable members 4 and 5. These members are slidably connected with each other and the member 4 has mounted thereon a clamp 6 to engage the member 5 as shown in dotted lines in Fig. 1 to thereby hold the member 1 properly positioned in the trousers leg. The members 4 and 5 are provided with longitudinal branch

portions 7 which are fitted slidably in the members 1 and 2. The longitudinal branch portions 7 are also of elliptical configuration in transverse section to form relatively narrow crease-forming surfaces 8.

55

With a view of providing means whereby the garment can be hung upon a suitable support after the crease-former has been connected therewith as described, I provide a support 9. This support is constructed from a single length of spring wire and it has an intermediate coiled portion 10, the relatively movable arms 11, and the hooks 12. The hooks 12 are adapted to be extended through the eyes 13 in the outer ends of the tubular members 1 and 2. The arms 11 have shoulders 14 thereon which are designed to engage against the eyes 13 so that under the tension of the spring support the tubular members 1 and 2 will be moved 60 slightly laterally on the branch portions 7 of the crease-former. This causes the tubular portions 1 and 2 and the portions 7 to be sprung relatively whereby to bind against each other to the extent that they will be effectually held in their desired longitudinally adjusted positions.

65

70

75

I claim:

1. In a garment hanger and stretcher, laterally adjustable members, means for holding said members in adjusted positions, tubular members slidably receiving the first members, and a support connecting the second members together and including relatively springy portions lying in mutual contact with the upper terminals of said second members and adapted to move said second members laterally against the first members so as to effect a binding action between the first and second members and thereby hold the second members against sliding adjustment upon the first members.

80

85

2. In a garment hanger and stretcher, the combination with laterally adjustable members having longitudinally extending branch portions disposed in downwardly diverging relation, tubular members telescoping said branches, and a spring connecting the upper terminals of said tubular members and including portions adapted for lateral separa-

tion relatively under the inherent elasticity of the spring and provided with shoulders for contacting with the tubular members at the upper ends thereof so as to move said members laterally on the branches of the first members to effect a binding action of the tubular members with the branches.

In testimony whereof I affix my signature in presence of two witnesses.

GABRIEL H. W. DOOSE.
